FREQUENCY-MODULATED CARRIER
SIGNAL RECEIVER

Harold A. Wheeler, Great Neck, N. Y., assignor,
by mesne assignments, to Hazeltine Research,
Inc., Chicago, Ill., a corporation of Illinois

Application March 11, 1940, Serial No. 323,290

9 Claims. (Cl. 250—20)

1

This invention relates to frequency-modulated carrier-signal receivers and more particularly to such receivers of the type including means for adjusting the selectivity of the receiver in accordance with a characteristic of a received signal.

Receivers for the reception of frequency-modulated carrier waves are subject to a certain amount of background noise which is more noticeable during the reception of a carrier wave having a weak frequency modulation thereon when the width of the frequency-modulation band is considerably less than the normal width of the pass band of the receiver selecting means which ordinarily has a fixed pass band that is sufficiently wide to pass a frequency-modulation band of the maximum width corresponding to the strongest modulation. Also, if the pass band of the receiver is greater than that required by the frequency-modulation band at any time, noise pulses are relatively great and are more noticeable in the reproduced signal.

Therefore, it is an object of the present invention to provide an improved frequency-modulated carrier-signal receiver which overcomes the above-mentioned disadvantages and undesirable features of such receivers of the prior art.

It is a further object of the invention to provide a frequency-modulated carrier-signal receiver including an automatic band width control system, whereby the band width is maintained just sufficient to pass the frequency-modulation band of the received signal without distortion.

In accordance with the invention, therefore, a frequency-modulation receiver, of the type including an intermediate-frequency amplifier and a frequency-modulation detector, comprises an intermediate-frequency feed-back circuit connected between the output and input circuits of the amplifier, means for deriving from the detected voltage a direct-current voltage whose magnitude is substantially proportional to the degree of modulation of the frequency-modulated waves, and means for varying the feedback through the feed-back circuit in response to the magnitude of the direct-current voltage to adjust the band width of the intermediate-frequency amplifier in accordance with the degree of modulation of the frequency-modulated waves.

For a better understanding of the present invention, together with other and further objects thereof, reference is had to the following description taken in connection with the accompanying drawing, and its scope will be pointed out in the appended claims.

The single figure of the drawing is a circuit 55

2

diagram, partially schematic, of a complete superheterodyne receiver adapter to receive a frequency-modulated carrier signal and comprising therein a control system in accordance with the invention for controlling the pass band of the receiver in response to and in accordance with the width of the frequency-modulation band of a received signal.

Briefly described, the receiver comprises a radio-frequency amplifier 10 having input terminals connected to an antenna system 11, 12 and output terminals coupled to a frequency changer or oscillator-modulator 13. Connected in cascade with oscillator-modulator 13, in the order 15 named, are an intermediate amplifier 14 of one or more stages, an adjustable band-pass selector 15, described more fully hereinafter, an intermediate-frequency amplifier and limiter 16, a frequency-modulation detector 17, an adjustable 20 volume control 18, an audio-frequency amplifier 19 of one or more stages, and a sound reproducer 20. Each of the elements or units 10-14, inclusive, and 16-20, inclusive, may be entirely conventional in construction so that a detailed 25 description is considered unnecessary herein.

Considering first the operation of the receiver as a whole, without regard to the details of the arrangement of the present invention, per se, a desired received frequency-modulated signal is 30 selected and amplified in the radio-frequency amplifier 10 and converted to an intermediate-frequency frequency-modulated carrier signal by the oscillator-modulator 13. The signal as thus converted is further amplified in intermediate-frequency amplifier 14, translated by the band-pass selector 15, further amplified and limited to a constant amplitude by intermediate-frequency amplifier and limiter 16, and detected by the frequency-modulation detector 17, thereby deriving the audio-frequency modulation components which are, in turn, translated by the adjustable volume control 18, amplified by audio-frequency amplifier 19, and reproduced by the sound reproducer 20.

45 Referring now more particularly to the details of the portion of the receiver embodying the present invention, the adjustable band-pass selector 15 comprises a tuned input circuit 22, 24, the inductance 22 of which is inductively coupled to an inductance 21 in the output circuit of amplifier 14, and a tuned output circuit 26, 27, the inductance 27 of which is inductively coupled to an inductance 28 in the input circuit of the amplifier and limiter 16. The two tuned terminal 50 circuits are coupled in the forward direction by

a vacuum tube 25 having input electrodes connected to the tuned terminal circuit 22, 24 and output electrodes coupled to the tuned terminal circuit 26, 27. The tuned terminal circuits 22, 24 and 26, 27 are also coupled in a backward direction by means of a vacuum tube 30, preferably similar in characteristics to the forward coupling tube 25 and having input electrodes inductively coupled to the tuned circuit 26, 27 by an inductance 29 and an output circuit inductively coupled to the tuned circuit 22, 24 by means of an inductance 31. A common unidirectional potential source, such as a battery 32, is provided for the screen-grid and anode circuits of vacuum tubes 25 and 30, while the grid circuits of the tubes 25 and 30 are returned to a common cathode terminal through a high-frequency by-pass condenser 42.

In order to derive a control effect, such as a control-bias voltage, by which to effect adjustment of the pass band of selector 15, there is coupled to the output circuit of the detector 17, independently of the volume control 18, an audio-frequency buffer amplifier 35 to which is coupled, by means of a transformer 36, a diode rectifier 37 provided with a load circuit including a resistor 39 shunted by a carrier-frequency by-pass condenser 49. The voltage developed across the load resistor 39 is applied positively, through an audio-frequency filter comprising a series resistor 38 and shunt condenser 41, to a control conductor 34 in opposition to a fixed bias from a suitable source such as a battery 33. The control conductor 34 is effective to apply the resultant bias to the control grid of each of the tubes 25 and 30. The load circuit of rectifier 37 has a relative fast charging rate corresponding to a small time constant of the order of $1/30$ second and a slow discharging rate corresponding to a large time constant of the order of one second so that the useful rectified output voltage is substantially unaffected by transient noise pulses to which the rectifier 37 may be subjected.

In considering the operation of that portion of the system comprising the present invention, it will be assumed that there is being received a signal having a wide frequency-modulation band corresponding to a strong modulation signal, which is accompanied by a large amplitude audio-frequency output from the frequency-modulation detector 17, which, after amplification in the buffer amplifier 35, is impressed on rectifier 37. The large rectified voltage output of rectifier 37 is sufficient to reduce to a minimum the negative bias from battery 33 applied to the grids of tubes 25 and 30, so that the transconductances of these tubes, the effective coupling between the tuned terminal circuits, and the pass band of the selector 15 are all at maximum values. When the width of the frequency-modulation band decreases in correspondence with a weak modulation signal, the rectified voltage output of rectifier 37 decreases, increasing the negative bias from battery 33 applied to the grids of tubes 25 and 30, to decrease their transconductances to a minimum. The coupling between the tuned terminal circuits is correspondingly decreased, reducing to a minimum the pass band of selector 15. The pass band of the selector 15 preferably is maintained only slightly wider than the width of the frequency-modulation band of a received signal so that the selector is effective to reduce noise to a maximum degree consistent with the signal being received; it is particularly effective during the reception of a weakly-modulated signal and in the absence of

any desired signal modulation, when noise is most objectionable. However, the pass band of selector 15 should never be reduced below twice the highest required audio frequency of modulation of a received signal.

It has been proposed in certain wide-band frequency-modulation systems to deviate the signal-carrier frequency a maximum of 75 kilocycles on either side of the mean carrier frequency, resulting in a maximum frequency-modulation band of somewhat greater than 150 kilocycles, and to allot to each channel a frequency band about 200 kilocycles wide. It has also been proposed in such systems to transmit an audio-frequency range having an upper limit of about 15 kilocycles which requires a minimum frequency-modulation band somewhat greater than 30 kilocycles to maintain fidelity of reproduction. Therefore, if the receiver of the invention is utilized in such a system, the pass band of selector 15 should be preferably adjustable between about 40 kilocycles and 200 kilocycles in response to variations in the strength of modulation of a received signal. However, in some cases it may be desirable to sacrifice the fidelity of reproduction in order to secure further reduction of noise during reception of a weakly-modulated signal. In such case, the minimum band width of the selector 15 may be reduced to 20 kilocycles or even to 10 kilocycles during reception of a very weakly-modulated signal. The maximum band width of the selector 15 in all cases, however, must be somewhat greater than the maximum width of the modulation band it is desired to reproduce.

The adjustable volume control 18 is provided in the main channel of the receiver for adjusting the loudness of reproduction of the reproducer 29 as desired. However, the auxiliary audio-frequency amplifier 35 for developing the control bias is coupled to the detector 17 in advance of the volume control 18, so that the band-width control bias is entirely independent of the adjustment of the volume control 18. Another desirable feature of the receiver described is that the rectifier 37 for developing the band width control bias is coupled to detector 17 through the buffer amplifier 35 so that it does not constitute a load on the main signal-translating channel, which would distort the audio-frequency signal in the main signal-translating channel. The use of like tubes 25, 30 in the forward and backward paths and the application of the same bias on the grids of both tubes provides the effect of a pair of coupled circuits with adjustable coupling by which the band width may be varied at least in the ratio of four-to-one, without substantially altering the gain of the selector.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A frequency-modulated carrier-signal receiver comprising, a carrier-frequency signal-translating channel including a band-pass selector, means for adjusting said band-pass selector to control the width of the pass band thereof, a frequency-modulation detector coupled to said channel, an adjustable volume control and signal-reproducing device coupled to said detector,

means coupled to said detector independently of said volume control and responsive to the detected signal amplitude for deriving a control effect, and means for utilizing said control effect to control said adjusting means to adjust the pass band of said selector directly in accordance with the degree of modulation of a received carrier signal.

2. A frequency-modulated carrier-signal receiver comprising, a carrier-frequency signal-translating channel including a band-pass selector comprising two terminal circuits and a pair of vacuum tubes individually coupling said terminal circuits in the forward and backward directions, means for adjusting said band-pass selector to control the width of the pass band thereof, a frequency-modulation detector coupled to said channel, rectifier means responsive to the detected signal amplitude for deriving a control-bias voltage, and means for applying said control-bias voltage to both of said vacuum tubes to adjust the pass band of said selector directly in accordance with the degree of modulation of a received carrier signal.

3. A method of frequency-modulation reception which includes collecting frequency-modulated waves in a circuit, amplifying a wide band of collected waves, establishing feedback of amplified waves during said amplification in such a manner as to widen the effective band width of the circuit, deriving modulation voltage from the amplified waves, deriving a unidirectional voltage from the modulation voltage whose magnitude is substantially proportional to the modulation amplitude, and controlling the said feedback with said unidirectional voltage.

4. A method of frequency-modulation reception which includes collecting frequency-modulated waves in a circuit, amplifying a wide band of collected waves, establishing feedback of amplified waves during said amplification in such a manner as to widen the effective band width of the circuit, deriving modulation voltage from the amplified waves, deriving a unidirectional voltage from the modulation voltage whose magnitude is substantially proportional to the modulation amplitude, and controlling the said feedback with said unidirectional voltage, and simultaneously controlling said amplification with said derived unidirectional voltage.

5. In a frequency-modulation receiver of the superheterodyne type including a signal collector, a converter, at least one intermediate-frequency amplifier, an amplitude-modulation limiter, means for deriving modulation voltage from the amplified frequency-modulated, intermediate-frequency voltage; the improvement which comprises means operatively associated with said intermediate-frequency amplifier for adjusting the effective pass band width of said amplifier, means for deriving from the said modulation voltage a unidirectional control voltage whose magnitude is directly proportional to the modulation voltage amplitude, means utilizing said control voltage for regulating the effectiveness of said band width adjusting means, said band width adjusting means comprising an intermediate-frequency voltage feed-back circuit connected between the output and input circuits of said amplifier, and said utilizing means applying said control voltage to said feed-back circuit in a sense to produce maximum pass-band width with maximum control voltage.

6. In a frequency-modulation receiver of the superheterodyne type including a signal collector,

a converter, at least one intermediate-frequency amplifier, an amplitude-modulation limiter, means for deriving modulation voltage from the amplified frequency-modulated, intermediate-frequency voltage; the improvement which comprises means operatively associated with said intermediate-frequency amplifier for adjusting the effective pass-band width of said amplifier, means for deriving from the said modulation voltage a unidirectional control voltage whose magnitude is directly proportional to the modulation voltage amplitude, and means utilizing said control voltage for regulating the effectiveness of said band width adjusting means, and additional means for applying said control voltage to said intermediate-frequency amplifier for increasing the gain thereof simultaneously with widening of said pass-band width.

7. In a frequency-modulation receiver of the type including an intermediate-frequency amplifier and a frequency-modulation detector, an intermediate-frequency feed-back circuit connected between the output and input circuits of said amplifier, means for deriving from the detected voltage a direct-current voltage whose magnitude is substantially proportional to the degree of modulation of the frequency-modulated waves, and means for varying the feedback through said feed-back circuit in response to the magnitude of said direct-current voltage.

8. In a frequency-modulation receiver of the type including an intermediate-frequency amplifier and a frequency-modulation detector, an intermediate-frequency feed-back circuit connected between the output and input circuits of said amplifier, means for deriving from the detected voltage a direct-current voltage whose magnitude is proportional to the degree of modulation of the frequency-modulated waves, and means for varying the feedback through said feed-back circuit in response to the magnitude of said direct-current voltage, said deriving means including a rectifier having an input circuit coupled to the detector output circuit.

9. In a frequency-modulation receiver of the type including an intermediate-frequency amplifier and a frequency-modulation detector, an intermediate-frequency feed-back circuit connected between the output and input circuits of said amplifier, means for deriving from the detected voltage a direct-current voltage whose magnitude is proportional to the degree of modulation of the frequency-modulated waves, and means for varying the feedback through said feed-back circuit in response to the magnitude of said direct-current voltage, said deriving means including a rectifier system having an input circuit coupled to the detector output circuit, and said rectifier system including a time-constant network constructed and arranged to permit development of said direct-current voltage at a rapid rate and discharge of the network at a relatively slow rate.
